UNITED STATES PATENT OFFICE

ABRAHAM SLATIS, OF CHICAGO, ILLINOIS

DESIGN FOR A RING OR SIMILAR ARTICLE

Application filed April 18, 1932. Serial No. 43,518. Term of patent 3½ years.

To all whom it may concern:

Be it known that I, ABRAHAM SLATIS, a citizen of the United States, residing at Chicago, in the county of Cook and State of Illinois, have invented a new, original, and ornamental Design for Ring or Similar Article, of which the following is a specification reference being had to the accompanying drawing, forming part thereof.

The drawing shows a perspective view of a ring embodying my design.

That part of the ring not fully shown in the drawing is a plain band.

I claim:

The ornamental design for a ring or similar article, substantially as shown and described.

ABRAHAM SLATIS.
